UNITED STATES PATENT OFFICE.

HERBERT E. STEVENS, OF WINDBER, AND BURT GELLATLY, OF PITTSBURG, PENNSYLVANIA, SAID GELLATLY, ASSIGNOR TO SAID STEVENS.

WIRE-SUSPENDING DEVICE.

SPECIFICATION forming part of Letters Patent No. 741,563, dated October 18, 1903.

Application filed June 26, 1903, Serial No. 163,230. (No model.)

To all whom it may concern.

Be it known that we, HERBERT E. STEVENS, a resident of Windber, in the county of Somerset, and BURT GELLATLY, a resident of Pittsburg, in the county of Allegheny, State of Pennsylvania, both citizens of the United States, have invented a new and Improved Wire-Suspending Device, of which the following is a full, clear, and exact description.

10 This invention relates to certain novel and useful improvements in means for suspending wires, especially electric trolley or feeder wires, from the rock or vault of a mine or from the metal or wooden roofs of buildings.

15 As is well known, heretofore considerable difficulty has been experienced in devising suitable means for suspending and securely retaining in position the feeder or trolley wires used in mines or elsewhere, wherein

20 electric haulage devices, such as locomotives, are used for the purpose of conveying the loaded ore or coal from the interior or chambers of a mine to the mouth thereof. Owing to the peculiar manner in which the kerf is

25 cut in the mines in following a lead or bank of coal, the tunnels or passages and the trolley-track and the conductor-wires therein must necessarily make many curves and turns to bring the car to the chamber where-
30 in the cutting is being done, and as the wire must be suspended at intervals from the roof of these crooked or twisted passage-ways it is very difficult to retain the wire-suspending means in position owing to the sagging or

35 lateral pressure exerted by the trolley-standard and wheel carried at its end upon the overhead wire when the car is rounding or turning a corner in said irregular passage-ways. This lateral pressure above referred

40 to when exerted upon the wire gradually loosens and finally causes the suspending means or supports to drop from their sockets in the roof of the mine. Such accidents as

45 these very often cause great delay, as a whole section of wire in a passage-way may thus be caused to fall to the ground and the work of haulage must cease until new supports are secured to the roof and the wire replaced

50 Therefore it is primarily the intention of the present invention to devise a suspending

means which shall obviate the difficulties above mentioned, such suspending means being so constructed and placed in the roof of the mine or building that it is very difficult 55 for the same to be forced or pulled therefrom.

A further object of the invention is to construct a device of this character which may be easily and readily placed in position and which after it has been decided to abandon 60 a passage-way in the mine may be quickly removed from the roof and used in another or new passage-way.

To the accomplishment of the hereinbefore-mentioned objects the invention consists in 65 the peculiar construction, combination, and arrangement of parts, as will be hereinafter fully described in this specification, illustrated in the drawings, and pointed out in the appended claims.

70 While we have herein shown and described in detail one particular and preferable embodiment of our improvement, it is of course to be understood that there can be modifications in various details without departing 75 from the spirit of the invention or sacrificing any of the advantages thereof.

75 Reference is to be had to the accompanying drawings, forming a part of this specification, in which similar characters of reference indicate corresponding parts in all the figures.

Figure 1 shows a section of the roof of a mine having a socket bored or cut therein, in which socket is inserted our improved suspending device; the view illustrating the manner in which the suspending bolt proper is adapted to be removed from the said socket. Fig. 2 is a view similar to Fig. 1, but showing our improved device when it is in position for use to hold the wires above described 85 suspended therefrom. Fig. 3 is a sectional view on the line 3-3 in Fig. 1, and Fig. 4 is a detail view of the improved bolt, forming a part of our suspension device.

Referring now to the drawings in detail, 90 the letter A designates the roof of a mine or the ceiling of a room, such part being shown in the present drawings in section and illustrates the manner of forming the socket or bore B therein. Into said bore or socket is 95 adapted to be inserted our improved wire-suspending device, which consists in the

2
present instance of a bolt, (shown in detail in Fig. 4,) such bolt comprising a relatively large elongated head portion, as at 1, which is formed upon the shank or spindle 2 of said bolt. This head portion of the bolt is clearly shown in Figs. 1 and 4 and extends about three-quarters of the entire length of the bolt proper. It is constructed, preferably, as shown, in the form or shape of a wedge approximately semicircular in cross-section and inclined along its straight edge, as at 3, from the top toward the lower or shank end of the bolt, so that such top part of the wedge-shaped portion of the bolt is relatively greater in cross-section than the bottom or shank portion thereof. As has heretofore been stated, this wedge portion is preferably formed integral with or as a part of the bolt and its straight edges 3 are inclined relative to the length of said bolt, and such edges extend outwardly from the bolt, as clearly shown in Fig. 4, forming a bearing or flange upon which is adapted to slide the second member of the bolt, which consists of a wedge-shaped grooved portion 4, approximately semicircular in cross-section and adapted when the main portion of the bolt has been inserted in the socket to slide upon the rounded un-wedged portion of the shank, its inclined face bearing upon the aforesaid inclined face 3 of the main bolt 1 and the rounded or outer faces of said bolt 4 bearing against the wall of the socket in such manner that it will force the bolt tightly against the opposite wall and cause the same to be securely held in said socket. When this wedge section 4 has been driven along the shank of the bolt into its proper position, the tapered or smaller end of said wedge portion is adapted to lie in the same horizontal plane with the enlarged or top portion of the head of the bolt. This is clearly shown in Fig. 2. To the reduced or shank portion of the bolt at 5, which is preferably screw-threaded, may be secured any suitable insulated supports or hangers for the trolley or feed wire.

The manner of using our improved bolt is substantially as follows: The bolt portion proper is first inserted into the socket until the top surface of the enlarged head is about three-quarters of an inch or other suitable distance below the bottom wall of such socket, a space being thus left between the head of the bolt and such bottom wall. The wedge section 4 is then driven into place and as it slides along the shank of the bolt will force the head tightly against the wall of the socket. When it is desired to remove the suspending device from the socket, it is only necessary to strike a sharp blow on the bottom of the shank of the bolt, when the head thereof will be driven up through the space above referred to until it abuts against the bottom wall of the socket, and this will cause the wedge section 4 to become loosened and to drop from the socket. The bolt thus being relieved of its fastening device will also fall from its posi-

tion. When the bolt is in its fastened or wedged position, it will be understood that the greater the downward pull upon the same or the more of lateral strain that is placed upon it the greater will be the wedging effect of the member 4. This renders it almost impossible for the motion of the car to loosen a bolt from its socket.

75
The many advantages incident to our improved wire-suspending device will be readily apparent, especially to those familiar with the art to which it pertains, and therefore it is unnecessary to dwell upon the same in detail here.

Having thus described our invention, we claim as new and desire to secure by Letters Patent—

1. A device of the class described, comprising a bolt having an enlarged inclined head portion, formed integral therewith and adapted to be placed in a suitable socket, and an inclined wedge-shaped member, sliding along the head of said bolt, when in position in said socket, such inclined wedge being adapted to bear against one of the walls of said socket and force the head of the bolt tightly against the opposite wall, substantially as set forth.

85
2. A device of the class described, comprising a bolt having formed integral therewith a relatively large inclined elongated head portion and a reduced end portion, such large elongated head portion being adapted to be inserted in a socket, and a removable wedge-shaped member approximately semicircular in cross-section, sliding on said enlarged integral head portion, and adapted to bear against the walls of the socket for retaining the head portion therein.

95
3. A device of the class described, comprising a bolt having formed integral therewith a relatively large elongated, wedge-shaped head portion and a reduced shank portion, said wedge-shaped portion being approximately semicircular in cross-section and tapering from its top toward the bottom or shank portion, said wedge-shaped portion being adapted to be inserted in a socket, and a separate, removable wedge-shaped member, approximately semicircular in cross-section and longitudinally grooved along its flat face, and having said face tapered from its bottom toward its top ends, such wedge-shaped member being adapted to slide along the bolt until its upper end is in the same horizontal plane with the upper end of the bolt-head, whereby said bolt will be securely wedged or held in place.

105
4. A device of the class described, comprising a bolt having formed integral therewith a relatively large, elongated head portion, and a reduced shank portion, said head portion being adapted to be inserted in a socket, such head portion being approximately semicircular in cross-section and having its flat longitudinal face tapered from a point approximately centrally of the upper end of the bolt to a point approximately near

the vertical longitudinal plane of the surface of the bolt, and a wedge-shaped member, approximately semicircular in cross-section and having its flat longitudinal face grooved, adapted to slide upon the bolt member when the latter is in position in the socket, and wedge or hold said bolt firmly therein.

In testimony whereof we have signed our

names to this specification in the presence of two subscribing witnesses.
